UNITED STATES PATENT OFFICE.

ADRIANUS ANTHONY WILTON VAN REEDE, CORNELISZON, OF SCHIEDAM, NETHERLANDS.

CRANKLESS ENGINE.

Application filed December 1, 1921. Serial No. 519,282.

To all whom it may concern:

Be it known that I, ADRIANUS ANTHONY WILTON VAN REEDE, CORNELISZON, a subject of the Queen of the Netherlands, residing at 5 Schiedam, Netherlands, have invented certain new and useful Improvements in Crankless Engines, of which the following is a specification.

The invention relates to an engine, having 10 its cylinders arranged parallel to its main shaft and pistons moving to and fro in said cylinders, the pistons being in permanent contact with a disc secured to the shaft in such a manner that the axis of the shaft is 15 not perpendicular to the plane of the disc but forms other than a right angle therewith, the disc being secured to a back-plate rigidly affixed to the shaft.

In consequence of the pressure exerted 20 by the pistons upon said inclined disc henceforth, called the swash plate, the latter is forced to turn round, if the cylinders remain stationary.

Similar engines are built so that the rigid 25 body mounted upon the shaft consists of a disc, placed obliquely and serving as a support for the pistons, having a reciprocating motion in their respective cylinders, and placed at both sides of said disc and parallel 30 to the axis of rotation of the main shaft.

In order to prevent said pistons from 35 losing contact with the disc or swash plate, each two opposed pistons are connected to each other outside the disc.

Evidently this construction requires good 40 workmanship and the slightest amount of play, caused by wear or other causes, has to be corrected immediately. This construction requires continuous and careful supervision.

The fact that the parts to be adjusted are 45 not readily accessible, increases the troubles enumerated.

This invention avoids all these difficulties 50 by having the pistons arranged in such a manner that they abut "quite free" against the swash plate but cannot lose contact with it because each piston, at the end opposite to that in contact with the swash plate, fits 55 in a space in which such a pressure can be given that the piston will always be adjacent to the swash plate.

The pistons being continuously pressed 60 against the oblique disc, wear of this part,

most exposed to friction, will not cause any 65 play.

The invention furthermore relates to a device procuring a simple and efficient means for one end of the piston to touch the oblique disc. To this end, each piston 70 is provided with a loose head rotatably movable and guided inside the piston and having an oblique face corresponding with the obliquity of the swash plate.

The requisite pressure in the chamber, 75 fitting the tail end of the piston can, according to the invention, be obtained by making a passage from this chamber to the cushion chamber of one of the other cylinders. In

this way the compression pressure made by 80 one piston may be utilized to keep one of the other pistons in contact with the swash plate. In a special form of the invention's realization, as a combustion engine, the 85 portion of the piston, that registers with the cushion chamber, is of a smaller diameter than the portion that does the work and, like this part, is made hollow and is pro-

vided with openings (18 in Fig. 1) in the 90 wall; said openings connecting the inside of the piston with the combustion chamber during the end of the stroke, while that portion of the cylinder which is situated at the side of the swash plate, being connected by ports, with the inside of the piston serves 95 the purpose of a pumping chamber for the scavenging and combustion air or for the mixture of fuel and air or the like.

In the accompanying drawings the invention has been further shown and explained, in which—

Fig. 1 is a vertical section through a plane of the axis of an engine according to the invention.

Fig. 2 is for one quarter, an end view and 95 for three quarters portions cross sections of this engine along the planes A—B, C—D, and E—F of Fig. 1.

The casing is formed by four cylinders 1, 100 cast in one piece and mounted upon a cylindrical portion 2, this latter being closed by a flat bottom 3. To the other side of the cylinders 1, a casting 4 is bolted, consisting of four cylindrical chambers 5, registering with the cylinders 1 but being of smaller 105 diameter. The extension 4 is provided with a centre piece 6.

In the bottom 3 and centre piece 6 and in

the casting of the cylinders 1, a shaft 7 is journalled in ball bearings. At one end said shaft may be provided with a coupling flange 8, while at the other end a fly wheel 9 can be mounted.

In the casing 2 and upon the shaft 7 a disc 10 is rigidly mounted, with a plane face and facing the pistons in an oblique position.

The cylinders contain step-pistons 11, the 10 central portion of which registers with the bore of the cylinders while one portion of smaller diameter registers with a corresponding chamber 5 and the other portion of smaller diameter registers with a corresponding 15 smaller bore of a corresponding cylinder.

The pistons are hollow but the portion near the swash plate 10 is separated from the rest by a partition 12 and is open at 20 its head. The space, thus formed carries a stem 13, journalled in ball bearings and having a head 14 outside of said space, the face of said head being bevelled, so as to register with and rest against the face 25 of the swash plate 10.

The space 15, situated at the side near the swash plate 10, is intended for the suction and first compression of the mixture of fuel and air. To this end, the cylinder 30 wall is provided with an inlet 16, which can be connected to the piping of a carburetor, the situation or position being such that during the compression stage, no gas can pass back to the carburetor. The cylindrical space 15 communicates with the inside of the hollow piston by means of apertures 17, while similar apertures 18 are provided in the other reduced portion of the piston.

40 The combustion and expansion space proper 19, is provided with outlet ports 20 in the usual manner.

The apertures 18 are so positioned that they connect the inside of the piston, which 45 contains the first compressed mixture, with the combustion chamber 19, after the outlet ports having been opened so far that an equalizatism has taken place.

The mixture then enters into the combustion chamber 19 and scavenges the products 50 of combustion towards the outlet port 20.

At the return stroke of the piston, the apertures 18 will be closed and, then also 55 the outlet ports, so that the second compression starts in after which, ignition, combustion and expansion will follow.

The pressures occurring in the cylinders and the forces accompanying the alternating 60 speeds of the pistons, will not always give a resultant in the direction towards the swash plate 10 and yet it is essential that the pistons should always abut the swash plate with some pressure.

65 The construction according to this invention provides for this by having mutual-

ly connected chambers 5 as shown at 5', 5", on Fig. 1 in which the air will be compressed by the return strokes of pistons 11, thus forming an air cushion giving the requisite pressure in the direction towards 70 the swash plate 10.

It is also possible to establish a communication between chambers belonging to different pistons and also to a special pressing medium, so that the diminution of the 75 space behind a piston may be utilized to press the pressing medium from this to another chamber with increasing space such as one which the piston is on its forward stroke. 80

Having now particularly described and ascertained the nature of my said invention and in what manner the same is to be performed, I declare that what I claim to be 85 my invention is:

1. A crankless engine comprising cylinders positioned parallel to a shaft in the engine, reciprocating pistons in the cylinders and having both ends projecting therefrom, the pistons engaging at one end a swash plate positioned obliquely to, and secured on, said shaft, said pistons abutting said obliquely positioned plate, but being wholly detached from said plate, and being pressed thereto by pressure applied at the 90 other ends of said pistons said pressure being applied exterior to said cylinders. 95

2. A crankless engine having cylinders positioned parallel to a shaft of the engine, reciprocating pistons therein, said pistons engaging at one end a swash plate positioned obliquely to, and secured to, said shaft, said pistons being wholly detached from said plate and held thereagainst by pressure applied at the idle end of said pistons, said pressure being effected by having a cushion chamber for one piston in communication with a similar chamber for another piston. 100

105 3. A crankless engine comprising cylinders positioned parallel to a shaft in the engine, reciprocating pistons in the cylinders, and having both ends projecting therefrom, the pistons engaging at one end a swash plate positioned obliquely to, and secured on, said shaft, said pistons abutting said obliquely positioned plate, but being wholly detached from said plate, and being pressed thereto by pressure applied at the other ends of said pistons, in each piston, said other end of the piston being made of smaller diameter than the piston proper, 110 said end and the remainder of the piston being hollow and provided with apertures in its wall, said apertures during the latter part of a stroke connecting the inside of the piston with the combustion chamber, while the portion of the cylinder adjoining 115 the swash plate, serves the purpose of a pumping chamber. 120

125 130

4. A crankless engine comprising cylinders positioned parallel to a shaft in the engine, reciprocating pistons in the cylinders, the pistons engaging at one end a
5 swash plate positioned obliquely to, and secured on, said shaft, said pistons abutting said obliquely positioned plate, but being wholly detached from said plate, and being pressed thereto by pressure, independent from that of the working charge, applied ^{to} 10 to said piston.

In testimony whereof I affix my signature.

ADRIANUS ANTHONY WILTON
van REEDE, CORNELISZON.
